2 SHEETS—SHEET 2.

UNITED STATES PATENT OFFICE.

CHARLES F. JORDAN, OF NEW YORK, N. Y.

CAR-DOOR LOCK.

1,361,159.

Specification of Letters Patent. Patented Dec. 7, 1920.

Application filed October 6, 1919. Serial No. 328,694.

To all whom it may concern:

Be it known that I, CHARLES F. JORDAN, a citizen of the United States of America, residing at New York, in the county of New 5 York and State of New York, have invented certain new and useful Improvements in Car-Door Locks, of which the following is a specification.

My present invention relates generally to 10 car door locks, and more particularly to the practical application in use of that type of car door lock embodying a seal, as shown in the application of John MacKenzie, Serial No. 289,325, which was filed April 11, 15 1919, my object being the provision of a practical, simple and durable mounting for the lock, as well as to provide against improper opening of the lock in such a way as to mutilate any of its parts.

20 A further object is the provision of means which will prevent improper opening of the lock and will in addition serve to provide for the use of a supplemental ribbon seal as now commonly used in connection with 25 freight car door locks.

With the above in mind, my invention resides in certain features to be hereinafter particularly pointed out, among those which

I will now describe, with respect to the accompanying drawings, forming a part of this specification, and in which

Figure 1 is a side elevation illustrating the practical application of my invention,

Fig. 2 is a front elevation of the lock and 35 its mounting removed,

Fig. 3 is a vertical longitudinal section, taken substantially on line 3—3 of Fig. 2,

Fig. 4 is a horizontal section taken substantially on line 4—4 of Fig. 1,

40 Fig. 5 is a partial horizontal section through the stop plate or lock mounting, taken along a line above the bolt housing, and

Fig. 6 is an elevation of the bolt lock 45 member removed.

Referring now to these figures, my invention is proposed in connection with a lock of the type including a chambered housing 15 through which the vertically shifting lock bolt 16 reciprocates. This bolt has an upper protecting cap 17 which in the lower effective position of the bolt, rests upon the top wall of the housing and covers a slot 18 through which a pan-shaped seal 19 may 50 be introduced when the bolt is elevated.

Thus the cap 17 in its effective position prevents the entrance of rain, snow or other extraneous matter within the housing.

When in position within the housing forwardly of the locking bolt 16, the seal 19 rests upon an inner shoulder of the housing, and the housing base like its top wall has guide openings for the bolt, and the seal is positioned forwardly of a spring bolt locking member 20 which is hung on a transverse pin 21 and which has two downwardly diverging wings, the outer or forward wing of which bears against the seal 19 and the rear or inner wing of which engages a notch 22 of the bolt 16, when the latter is 70 thrust downwardly to locked position.

The housing 15 is open at the front and the seal 19 normally covers this opening so as to prevent access to the bolt locking member 20 until after the seal is ruptured.

75 In its lower locked position, the locking bolt 16 projects beneath the housing 15 and through an apertured ear 23 which forms a staple and which receives the door carried hasp 24 thereover, and the lower extremity 80 of the bolt 16 is slotted as at 25 for the reception of the usual ribbon car seal 26, shown in Fig. 1.

In accordance with my present improvements, the lock housing 15 is mounted on 85 and integral with a door stop plate 27 which forms the lock mounting and which is preferably a casting having three sides to adapt the same to fit over the inner ends of the door stop strips 28 of a car side, which the 90 casting overlaps sufficiently to receive bolt 29 through its openings above and below the lock housing 15.

The lock mounting or stop plate has a brace or bracket arm 30 projecting laterally 95 therefrom at one side to receive a bolt 31 through the car side and has an oppositely extending intermediate door engaging lip 32.

Furthermore, and in accordance with my 100 present improvements the lock mounting or stop plate 27 has an outstanding lug 33 below and spaced from the staple 23, which is arranged in the vertical line of the lock bolt 16 and projects from the stop plate 105 slightly beyond the plane of the lock bolt. The lug 33 is furthermore so positioned with respect to the lock housing and the length of the bolt 16 as to receive the lower free end of the bolt thereagainst in the 110

lower locked position of the bolt in order to prevent the use of a hammer or other tools against the lower end of the bolt for the purpose of forcing the latter vertically 5 to released position without first rupturing the seal 19 and releasing the bolt by swinging the spring locking member 20 in an outward direction.

It is obvious that although the bolt could 10 not be forced vertically to released position, while the seal 19 is in place, without showing evidence thereof, careless persons might, rather than rupture the seal and spring the locking member outwardly, simply force 15 the bolt vertically, which would itself rupture the seal in all probability and which would obviously ruin the spring locking member 20.

With the lug 33 in position, the bolt can 20 not be struck and forced vertically to released position or pried upwardly. The lug also serves a further function by virtue of its provision with an inner vertically extending shoulder portion 34 inwardly beyond 25 the plane of the bolt 16 with respect to the stop plate or mounting 27 which shoulder portion has a slot 35 thus arranged to align horizontally with the slot of the lower end of bolt 16 for the reception of the 30 usual ribbon seal, supplementing the seal 19 above described.

The above described mounting for the lock and my improvements in connection therewith are designed to fulfill all requirements 35 for the practical introduction of car door locks of the above type, and obviously avoid disadvantages due to carelessness which would arise in its practical operation.

I claim:—

1. A car door lock comprising a mounting or support, a locking mechanism thereon including a vertically movable locking bolt provided with a seal receiving slot adjacent to its lower free end, and a seal controlled spring locking member engaging the bolt 40 in its lower position, and a lug carried by the said mounting or support in line with the bolt, receiving the free end of the bolt in abutting relation thereagainst in the locked position and provided with a 45 shoulder inwardly beyond the plane of the bolt having a slot to coöperate with the bolt slot for the reception of a seal, as described.

2. A car door lock comprising a supporting plate, a locking mechanism on the plate 55 including a lengthwise movable locking bolt having a slot adjacent to its free end and shiftable in parallel spaced relation to the plate and a seal controlled spring locking member engaging the bolt in its lower position, and a lug carried by the plate in line with the axis of the bolt said lug projecting from the plate beyond the plane of the bolt and positioned to receive the free end of the bolt in abutting relation when the bolt is in 60 locked position, and having an inner shouldered portion located between the supporting plate and the plane of the bolt, provided with a transverse slot arranged parallel to the adjacent face of the supporting plate to 65 coöperate with the bolt slot as and for the purpose set forth.

In testimony whereof I affix my signature.

CHARLES F. JORDAN.
